UNITED STATES PATENT OFFICE

MARCEL CHRISTEN, OF NEW YORK, N. Y., ASSIGNOR TO GOLDSSTEIN-WILKINS CORPORATION, OF NEW YORK, N. Y., A CORPORATION OF NEW YORK

DESIGN FOR A TEXTILE FABRIC

Application filed May 22, 1933. Serial No. 48,188. Term of patent 3½ years.

To all whom it may concern:

Be it known that I, MARCEL CHRISTEN, a citizen of United States, residing at the city of New York, in the county of Queens and State of New York, have invented a new, original, and ornamental Design for a Textile Fabric, of which the following is a specification, reference being had to the accompanying drawing, forming part thereof.

The figure is a plan view of a textile fabric, showing my new design. The design as shown is one including a selvage. This selvage is shown at the left side of the drawing.

I claim:

The ornamental design for a textile fabric, substantially as shown and described.

MARCEL CHRISTEN.
